The ornamental design for a trash can, as shown and described.

DESCRIPTION

FIG. 1. is a top perspective view of a trash can showing a first embodiment of my new design;

FIG. 2. is a front view of a trash can of FIG. 1;

FIG. 3. is a rear view of a trash can of FIG. 1;

FIG. 4. is a left view of a trash can of FIG. 1;

FIG. 5. is a right view of a trash can of FIG. 1;

FIG. 6. is a top view of a trash can of FIG. 1; and,

FIG. 7. is a bottom view of a trash can of FIG. 1.

The broken lines shown in the figures are included for the purpose of illustrating portions of the trash can and forms no part of the claimed design.
